CLAIM

The ornamental design for a fishing rattler, as shown and described.

DESCRIPTION

FIG. 1 is a perspective view of a fishing rattler showing my new design;

FIG. 2 is a front elevational view thereof, the rear elevational view being a mirror image thereof;

FIG. 3 is a right side elevational view thereof, the left side being a mirror image thereof;

FIG. 4 is a top plan view thereof;

FIG. 5 is a bottom plan view thereof; and,

FIG. 6 is a bottom plan view taken along line 6—6 of FIG. 4.
